UNITED STATES PATENT OFFICE.

ALLAN ARCHIBALD CAMERON, OF CHICAGO, ILLINOIS.

DESIGN FOR AN AUTOMOBILE RADIATOR-CAP ORNAMENT.

Application filed July 16, 1927. Serial No. 22,774. Term of patent 7 years.

To all whom it may concern:

Be it known that I, ALLAN ARCHIBALD CAMERON, a citizen of the United States, residing at 1545 East Marquette Road, city of Chicago, in the county of Cook and State of Illinois, have invented a new, original, and ornamental Design for an Automobile Radiator-Cap Ornament, of which the following is a specification, reference being had to the accompanying drawing, forming a part thereof.

Figure 1 is a side elevation of an automobile radiator cap ornament, showing my new design,

Fig. 2 is a front view thereof,

Fig. 3 is a rear view, and

Fig. 4 is an elevation of the other side thereof.

I claim:

The ornamental design for an automobile radiator cap ornament, as shown.

ALLAN ARCHIBALD CAMERON.
